UNITED STATES PATENT OFFICE.

NOVALIS LACROIX, OF BELLE CENTER, OHIO.

HOISTING APPARATUS.

1,157,557.

Specification of Letters Patent.

Patented Oct. 19, 1915.

Application filed August 11, 1914. Serial No. 856,288.

To all whom it may concern:

Be it known that I, NOVALIS LACROIX, a citizen of the United States, residing at Belle Center, in the county of Logan and State of Ohio, have invented certain new and useful Improvements in Hoisting Apparatus, of which the following is a specification, reference being had to the accompanying drawings.

10 This invention relates to an improved hoisting apparatus and has for its primary object to provide manually operable means for hoisting wagon bodies, hay racks and the like, having certain improved structural features whereby the same may be operated with ease and facility.

In its more specific aspect, the present invention provides two pairs of beams mounted upon opposite sides of a suitable 20 frame structure and fulcrumed intermediate of their ends, a drum or windlass rotatably mounted in the frame, and flexible connections detachably engaged therewith and connected to the respective beams, means centrally secured to the windlass for rotating the same, and additional means for locking the windlass against rotation to retain the beams in various angular positions.

The invention has for a further object to 30 produce an apparatus of the above character, whereby two bodies may be simultaneously elevated, or one of the bodies raised while the other is lowered, said apparatus being provided with means for anchoring any one 35 of the beams to the frame structure, whereby the body which has been lifted thereby may be disposed at an inclination to discharge its contents into a storage bin.

The invention has for an additional object 40 to provide a hoisting apparatus which is simple and inexpensive in its construction, as well as strong and durable and of great convenience in practical use.

With the above and other objects in view, 45 the invention consists in novel features of construction, combination and arrangement of parts as will be hereinafter referred to and more particularly pointed out in the specification and claims.

50 For a full understanding of the invention, reference is to be had to the following description and accompanying drawings, in which—

Figure 1 is a side elevation of a hoisting apparatus constructed in accordance with the preferred embodiment of my invention;

Fig. 2 is a top plan view thereof; Fig. 3 is an enlarged elevation of the drum or windlass; Fig. 4 is a section taken on the line 4—4 of Fig. 3; Fig. 5 is an enlarged elevation of one of the beams, illustrating a slightly modified construction thereof. Figs. 6 and 7 are detail sectional views taken on the lines B—B and C—C, respectively, of Fig. 3.

Referring in detail to the drawings, 5 designates the frame structure which may be of any desired proportions, and is suitably braced to sustain the strains which will devolve thereon in the use of the apparatus. This frame structure, is preferably, though not necessarily, mounted upon suitable runners, indicated at 6, whereby the apparatus may be readily moved from place to place. Upon the upper longitudinal bars 7 of the frame structure and adjacent to each end thereof, a U-shaped clip 8 is secured.

9 designates the beams, each of which is equipped with a loop 10, said loop being engaged in one of the clips 8 and having its ends pivotally secured upon opposite sides 80 of the beam at its center. The upper edge of each of the beams 9 has a longitudinally extending metal strap 11 secured thereon, the ends of which are bent around the ends of the beam and secured to the lower edge 85 thereof, thereby producing the eyes, indicated at 12.

A drum or windlass 13 is provided upon its end with trunnions 14 which are journaled in suitable bearings mounted upon opposite ends of the frame structure 5. The ends of the drum are reinforced by the flanged sleeves or collars 15. A metal sleeve 16 is also secured upon the drum 13 centrally thereof, by means of the screws indicated at 90 17, and in this sleeve the inner ends of the radially disposed spokes of an operating wheel 18 are secured two of them extending in one continuous piece through the drum 13. Pins 19, extend at right angles to each 95 other also through the sleeve 16 and the drum, and project radially from the periphery of the drum. These pins are adapted to be received in an opening 21, provided in a locking lever 20 which is fulcrumed at one 100 of its ends, as at 22, upon the frame structure 5. This pivoted end of the lever is very loose so as to admit of its vertical movement. It will be understood that when the locking lever is engaged with one of the pins 110 19, the drum or windlass 13 will be held against rotation. To each end of the drum

13 and in spaced relation longitudinally thereof, the screws or bolts 23 are fixed in opposite sides of the drum. Chains, cables or other suitable flexible elements indicated at 24 are provided with rings or eyes 25 upon one of their ends for detachable engagement with said headed bolts. The other ends of the respective chains are provided with hooks for engagement with the eyes 12 on the inner ends of the beams 9.

25 designates a hay rack which is suspended by means of suitable chains 26 from the ends of the beams 9 projecting beyond one side of the frame 5. A wagon body, shown at 27, is similarly connected by the chains 28 with the oppositely extending beams. It will be noted from reference to Fig. 3 that the chains 24 extending downwardly from the inner ends of one pair of beams are engaged with the corresponding screws or bolts 23 at opposite ends of the drum 13 while the chains on the inner ends of the other pair of beams extend downwardly on the opposite side of the drum and are connected to the other bolts 23. It is thus apparent that when the drum is rotated through the medium of the operating wheel 18 in the direction indicated by the arrow, the wagon body 27 will be raised or elevated while the rack 25 will be lowered. After the wagon body and its contents have been thus lifted to the desired height, the locking lever 20 is engaged with one of the pins 19 so as to hold the drum against reverse rotation. Each of the beams 9 is further provided upon its inner end with a hook 29 for engagement by an eye or ring attached to a short chain or cable indicated at 30, which is secured to the frame 5. By now anchoring one of the beams 9, the drum may be released and its rotation reversed so that one end of the wagon body 27 will be lowered, thus disposing the same at a longitudinal inclination to effect the discharge of its contents into the silo or other storage bin. By providing a detachable connection between the chains 24 and the drum 13, these chains may be so connected to the drum as to operate the two pairs of beams in unison and simultaneously hoist the wagon bodies or other objects suspended from their outer ends. When the chains 26 and 28 are unhooked from their loads which they have raised or lowered, the inner ends of the beams being slightly heavier than their outer ends, these will move downwardly, the chains 24 sagging below the drum 13. By the provision of the anchoring means for the beams and their detachable connection with the drum, said beams may be operated either singly, or in pairs.

In Fig. 5 of the drawings I have shown a slightly modified construction of the beams 9, wherein the extremities of the metal reinforcing strap 11' are disposed at right an-

gles and extended below the lower edge of the beam. Additional metal plates 31 are secured to the lower edge of the beam at its ends and have angularly disposed extremities 32 which are engaged with the ends of the strap 11'. These engaged end portions of the metal strap and the plates 31 are provided with openings to receive the hooks on the ends of the chains.

From the foregoing description taken in connection with the accompanying drawings, the construction, manner of operation and several advantages of my invention will be apparent. By mounting the operating wheel 18 centrally upon the drum or windlass, the device may be operated with a minimum of manual labor, as the objects suspended from the outer ends of the respective pairs of beams substantially balance each other. The invention is also highly serviceable for expeditiously emptying wagons containing corn or other farm products and storing such products in the corn crib or silo.

The apparatus as a whole is comparatively simple in its construction and may be produced at small manufacturing cost.

While I have described and shown the preferred arrangement and construction of the several elements employed, it will be understood that the invention is susceptible of considerable modification in the proportions and materials employed in its construction and I therefore reserve the privilege of resorting to all such legitimate changes in these respects as will be fairly embodied within the spirit and scope of my invention as claimed, without changing any essential feature of its mechanical operation.

I claim:

1. In an apparatus of the character described, the combination of a frame, two pairs of beams fulcrumed intermediate of their ends in the frame, the respective pairs of beams projecting from opposite sides of the frame, a drum mounted in the frame, flexible elements connected to the inner ends of the beams and adapted for detachable connection with said drum, a wheel centrally secured to the drum whereby the same may be rotated to oscillate said beams, pins projecting radially from the drum, and a lever fulcrumed at one end in the frame and provided with an opening to receive any one of said pins whereby the drum is held against rotation.

2. In an apparatus of the character described, the combination with a frame, two pairs of beams fulcrumed intermediate of their ends in said frame, the respective pairs of beams projecting from opposite sides of the frame, a drum rotatably mounted in said frame, stud bolts fixed in opposite sides of the drum at each end thereof and spaced from each other longitudinally of the drum, flexible elements connected to the inner ends

of the beams and adapted for detachable connection with said studs, a sleeve centrally secured upon the drum, a wheel mounted upon said sleeve to rotate the drum, 5 radially disposed pins extending through the drum and sleeve, a locking lever fulcrumed at one end upon the drum and provided with an opening to receive any one of said pins, a hook secured to the inner end 10 of each of the beams, and anchoring means

for engagement with said hooks to secure any one of the beams against movement with respect to the frame.

In testimony whereof I hereunto affix my signature in the presence of two witnesses. 15

NOVALIS LACROIX.
